ARTICLE SUPPORTER, SUPPLY DEVICE,
AND IMAGE FORMING APPARATUS

The entire disclosure of Japanese patent Application No. 2022-074640, filed on Apr. 28, 2022, is incorporated herein by reference in its entirety.

BACKGROUND

Technological Field

The present invention relates to an article supporter that supports a thinly tabular article, a supply device including the article supporter, and an image forming apparatus.

Description of the Related Art

Regarding to an image forming apparatus, JP 2016-204080 A discloses a technique of detecting the rear end of an envelope in the tray accommodating the envelope to be an image forming target.

Such an image forming apparatus has a tray that accommodates thinly tabular articles as a bundle of stacked articles. In a case where a thinly tabular article is partially different in thickness such as an envelope, the uppermost thinly tabular article in the bundle is inclined due to stacking of the articles difference in thickness. The inclined thinly tabular article may interfere with the outward supply from the tray. Thus, the number of stacked thinly tabular articles is limited to a small number.

SUMMARY

The present invention has been made in view of the above points. An object of the present invention is to provide an article supporter capable of suitably supporting a bundle of a plurality of thinly tabular articles that is stacked and is partially different in thickness, a supply device, and an image forming apparatus.

To achieve the abovementioned object, according to an aspect of the present invention, there is provided an article supporter for a supply device including a feeder that supplies, by air suction, an uppermost thinly tabular article from a bundle of a plurality of thinly tabular articles that is stacked and is partially different in thickness, the article supporter for supporting the bundle with a gap between the uppermost thinly tabular article and the feeder, the article supporter reflecting one aspect of the present invention comprises: a first support that supports respective thinner parts of the plurality of thinly tabular articles; a second support that supports respective thicker parts of the plurality of thinly tabular articles and is movable upward and downward; and an adjuster that adjusts a level of the second support such that the uppermost thinly tabular article of the bundle is set within a predetermined range in a vertical direction.

BRIEF DESCRIPTION OF THE DRAWINGS

The advantages and features provided by one or more embodiments of the invention will become more fully understood from the detailed description given hereinbelow and the appended drawings which are given by way of illustration only, and thus are not intended as a definition of the limits of the present invention.

2

FIG. 1 is a perspective view schematically illustrating a supply device according to an embodiment of the present invention;

5 FIG. 2 is a side view (cross-sectional view taken along line II-II in FIG. 1) schematically illustrating the supply device according to the embodiment of the present invention;

10 FIG. 3 is a perspective view schematically illustrating an article supporter set for use in the supply device according to the embodiment of the present invention;

15 FIG. 4 is a side view schematically illustrating the article supporter set for use in the supply device according to the embodiment of the present invention;

20 FIG. 5 is a rear view schematically illustrating a longitudinally-long open-end envelope as an exemplary thinly tabular article;

25 FIG. 6 is a rear view schematically illustrating a center-seam elongated open-end envelope as an exemplary thinly tabular article;

30 FIG. 7 is a rear view schematically illustrating a single-side-seam elongated open-end envelope as an exemplary thinly tabular article;

35 FIG. 8 is a plan view schematically illustrating an example that a longitudinally-long open-end envelope end is supported by the article supporter set according to an embodiment of the present invention;

40 FIG. 9 is a side view schematically illustrating an example that the longitudinally-long open-end envelope is supported by the article supporter set according to the embodiment of the present invention;

45 FIG. 10 is a side view schematically illustrating an example that the longitudinally-long open-end envelope is supported by the article supporter set according to the embodiment of the present invention;

50 FIG. 11 is a plan view schematically illustrating an example that a center-seam elongated open-end envelope is supported by an article supporter according to an embodiment of the present invention;

55 FIG. 12 is a side view schematically illustrating an example that the center-seam elongated open-end envelope is supported by the article supporter according to the embodiment of the present invention;

FIG. 13 is a plan view schematically illustrating an example that a single-side-seam elongated open-end envelope is supported by the article supporter according to the embodiment of the present invention;

FIG. 14 is a rear view schematically illustrating an example that the single-side-seam elongated open-end envelope is supported by the article supporter according to the embodiment of the present invention; and

FIG. 15 is a side view schematically illustrating an image forming apparatus according to an embodiment of the present invention.

DETAILED DESCRIPTION OF EMBODIMENTS

Hereinafter, one or more embodiments of the present invention will be described with reference to the drawings. However, the scope of the invention is not limited to the disclosed embodiments. In the reference drawings, "front and rear" indicates a feeding direction of a thinly tabular article (the downstream side as front and the upstream side as rear), and "left and right" indicates a width direction of the thinly tabular article (a direction orthogonal to the feeding direction and the up-and-down direction).

<<Supply Device>>

As illustrated in FIGS. 1 and 2, a supply device 1 according to an embodiment of the present invention is of an air separation type. The supply device 1 blows air to a plurality of thinly tabular articles 2 stacked in the up-and-down direction to float and separate each thinly tabular article 2, and then conveys the separated thinly tabular article 2 to supply outward. The supply device 1 includes, as a basic configuration, a bottom wall 201, a front wall 202, a lifting plate 203, a position regulator 204, a pair of left and right floaters 205 and 205, a front floater 206, and a feeder 210. The supply device 1 further includes sensors 221 and 222, and a controller 223.

<<Bottom Wall>>

The bottom wall 201 extending horizontally (frontward and rearward, and leftward and rightward) serves as a floor face of the supply device 1.

<<Front Wall>>

The front wall 202 extends upward from the front end of the bottom wall 201. The front wall 202 serves as a position regulator that regulates the position of the respective front ends of the thinly tabular articles 2 provided on the lifting plate 203 (i.e., frontward movement of the thinly tabular article 2).

<<Lifting Plate>>

The lifting plate 203 provided above the bottom wall 201 extends horizontally, and is a tabular metal member movable upward and downward. The lifting plate 203 has, for example, a hole and a cutaway for allowing movement of the position regulator 204 and each floater 205.

<<Position Regulator>>

The position regulator 204 protudes upward the lifting plate 203 on the upper side of the bottom wall 201. The position regulator 204 regulates the position of the respective rear ends of the thinly tabular articles 2 provided on the lifting plate 203 (i.e., rear movement of the thinly tabular article 2.) The position regulator 204 manually movable frontward and rearward with respect to the bottom wall 201 can correspond to thinly tabular articles 2 various in size.

<<Floater>>

Each of the pair of floaters 205 and 205 protudes upward the lifting plate 203 on the upper side of the bottom wall 201, and serves as a fan that blows air from the corresponding side to the uppermost thinly tabular article 2 of the thinly tabular articles 2 provided on the lifting plate 203 to float the thinly tabular article 2. The floater 205 manually movable leftward and rightward with respect to the bottom wall 201 can correspond to thinly tabular articles 2 various in size. The floater 205 is accommodated in the corresponding housing serving as a position regulator that regulates the position of the respective ends in the width direction of the thinly tabular articles 2 provided on the lifting plate 203 (i.e., movement in the width direction of the thinly tabular articles 2).

<<Floater>>

The floater 206 serves a fan that blows air from the front of the uppermost thinly tabular article 2 of the thinly tabular articles 2 provided on the lifting plate 203 to float the thinly tabular article 2.

<<Feeder>>

The feeder 210 provided above the front wall 202 conveys the thinly tabular article 2 floated by the floater 206 with the floated thinly tabular article 2 sucked by air to feed the sucked thinly tabular article 2 outward (frontward) the supply device 1. The feeder 210 includes a driving roller 211, a driven roller 212, a suction belt 213 as an endless belt that has a plurality of holes and is wound around the driving

roller 211 and the driven roller 212, and a sucker 214 provided on the inner circumferential side of the suction belt 213.

<<Sensor>>

5 The sensor 221 provided at the lifting plate 203 detects (presence or absence of) the thinly tabular article 2 provided above the sensor 221 to output the detection result to the controller 223. The sensor 222 provided at the upper part of the front wall 202 detects (presence or absence of) the thinly tabular article 2 present at the same level as the sensor 222 to output the detection result to the controller 223.

<<Controller>>

The controller 223 includes a central processing unit (CPU), a read-only memory (ROM), a random access memory (RAM), and an input/output circuit. In response to detection of the thinly tabular articles 2 by the sensor 221, the controller 223 controls a mechanism such as a motor (not illustrated) to cause the lifting plate 203 to lift. Here, in response to the detection of the thinly tabular articles 2 by the sensor 222, the controller 223 stops the mechanism (not illustrated) to set the lifting plate 203 (i.e., the uppermost thinly tabular article 2) to a desired level. The gap C between the uppermost thinly tabular article 2 and the feeder 210 (the 15 lower face of the suction belt 213) is set to a predetermined value. In such a state, the floaters 205 and 206 can blow air to the uppermost thinly tabular article 2. The suction belt 213 locates above the uppermost thinly tabular article 2 by a predetermined level.

20 Subsequently, the controller 223 controls the floaters 205 and 206 to float the uppermost thinly tabular article 2. Further, the controller 223 controls the sucker 214 to suck the floated thinly tabular article 2 such that the floated thinly tabular article 2 is sucked onto the suction belt 213 (by air 25 suction), and controls, for example, a motor for rotating the driving roller 211, so that the thinly tabular article 2 sucked on the suction belt 213 is conveyed and supplied outward the supply device 1 while being conveyed.

<<Article Supporter Set>>

30 As illustrated in FIGS. 3 and 4, in order for the supply device 1 supplying, such as an envelope, a thinly tabular article 2 partially different in thickness, the article supporter set 4 according to the embodiment of the present invention is provided on the lifting plate 203 to support the bundle 3 as a stacked body including a plurality of thinly tabular articles 2. The article supporter set 4 includes an article supporter 5, and a pair of auxiliary article supporters 6 and 6.

<<Article Supporter>>

35 The article supporter 5 includes a pair of bases 10 and 10, a position regulator 20, and a coupler 30. The article supporter 5 further includes, for each base 10, a first support 40, a second support 50, an adjuster 60, a raising member 70, and a pair of front and rear third supports 80 and 80.

<<Base>>

40 Each of the pair of bases 10 and 10 is an elongated tabular metal member extending in the feeding direction of the thinly tabular article 2, that is, frontward and rearward. Each of the pair of bases 10 and 10 is securable to the lifting plate 203 by magnetic force. The one of the pair of bases 10 and 10 and the other are provided in parallel to each other at a predetermined interval in the width direction. In the present embodiment, the pair of bases 10 and 10 are two sides that are each a metal member having a rectangular frame shape and that faces each other. That is, the respective front ends of the pair of bases 10 and 10 are integrally connected through a front side part 11 extending in the width direction,

and the respective rear ends of the pair of bases **10** and **10** are integrally connected through a rear side part **12** extending in the width direction.

<Position Regulator>

The position regulator **20** is a resin member coupling the front ends of the pair of bases **10** and **10** to each other, and regulates the position of the front end of the bundle **3** as the stacked body including the plurality of thinly tabular articles **2** supported by the article supporter **5**. The position regulator **20** integrally includes a bottom wall **21**, a front wall **22** extending upward from the front end of the bottom wall **21**, and an extending wall **23** extending upward from an intermediate part in the width direction of the upper end of the front wall **22**. The rear end of the bottom wall **21** is secured to the front ends of the pair of bases **10** and **10** and the front side part **11**. The respective rear faces of the front wall **22** and the extending wall **23** each are arc-shaped about pivotal shafts **A1** and **A2** in side view.

The position regulator **20** includes a plurality of ribs **24** each erected rearward from the rear faces of the front wall **22** and the extending wall **23**. The plurality of ribs **24** each extend upward and downward and are disposed at equal intervals in the width direction. The respective leading ends (rear end faces) of the plurality of ribs **24** are each arc-shaped about the pivotal shafts **A1** and **A2** in side view.

<Coupler>

The coupler **30** is a resin member coupling the rear ends of the pair of bases **10** and **10** to each other. The coupler **30** integrally includes a bottom wall **31** and a rear wall **32** extending upward from the rear end of the bottom wall **31**. The front end of the bottom wall **31** is secured to the rear ends of the pair of bases **10** and **10** and the rear side part **12**. The rear wall **32** has an upper part provided with a handle **33**. The handle **33** having a hole penetrating the rear wall **32** frontward and rearward is grippable by the user.

The coupler **30** includes a lower protrusion extending downward from the bottom wall **31**. The lower protrusion is internally fitted into a groove extending frontward and rearward at a central part in the width direction of the lifting plate **203**, thereby regulating movement of the coupler **30** in the width direction and positioning the article supporter **5** in the width direction.

<First Support>

Such a first support **40** as described above is a resin member integrally including a bottom wall **41** and a pair of side walls **42** and **42** extending upward, one-to-one, from both ends of the bottom wall **41** in the width direction. The bottom wall **41** is substantially the same in width dimension as the base **10**, and is attached to an intermediate part in the longitudinal direction of the base **10**. The first support **40** supports a portion where the respective thinner parts **2X** of the thinly tabular articles **2** of the bundle **3** are superimposed on the respective upper faces of the pair of side walls **42** and **42** (see FIG. 8).

Each side wall **42** integrally includes a lower part **42a**, an inclined part **42b**, and an upper part **42c**. The lower part **42a** is wide in width in the front-and-rear direction. The inclined part **42b** extends upward from the upper end of the lower part **42a**, narrows upward in width, and has a front side inclining rearward. The upper part **42c** extends upward from the inclined part **42b** and is narrower in width than the lower part **42a** in the front-and-rear direction. The inclined part **42b** is a part provided for avoiding interference with an intermediate part **52** of the second support **50**. The upper part **42c** is a part to which the raising member **70** to be described later is attached.

<Second Support>

Such a second support **50** described above extends frontward and rearward and is a resin member integrally including a base end **51**, the intermediate part **52**, and a leading end **53** in this order from the rear. The base end **51** is accommodated between the pair of side walls **42** and **42**, and is journaled pivotally around the pivotal shaft **A1** to the pair of side walls **42** and **42**. With no bundle **3** supported, the base end **51** inclines upward from rear to front in side view. With no bundle **3** supported, the intermediate part **52** inclines upward from rear to front in side view. The intermediate part **52** inclines inward in the width direction from rear to front in plan view. With no bundle **3** supported, the leading end **53** extends almost horizontally in side view. The second support **50** supports a portion where the respective thicker parts **2Y** of the thinly tabular articles **2** of the bundle **3** are superimposed on the upper face of the leading end **53** (see FIG. 8). Further, at least either the first support **40** or the second support **50** is provided with a pivotal regulator that regulates, with no bundle **3** supported, pivoting of the second support **50** such that the leading end **53** does not move upward from its horizontal position.

The leading end **53** includes a sensor holder **53a** as a recess capable of holding a sensor **221**, and a through hole **53b** with which the bottom face of the sensor holder **53a** is provided. The sensor **221** is detachably attached to each of the lifting plate **203** and the sensor holder **53a** of the leading end **53**. The sensor **221** accommodated and held in the sensor holder **53a** is connected to the controller **223** through a wired line passing through the through hole **53b**.

<Adjuster>

The adjuster **60** adjusts the level of the leading end **53** of the second support **50** such that the uppermost thinly tabular article **2** of the bundle **3** is set within a predetermined range **R** (see FIG. 9) in the vertical direction. That is, the difference in level between the positions in the plane of the uppermost thinly tabular article **2** is set within the predetermined range **R**, and thus the uppermost thinly tabular article **2** is in a substantially horizontal posture. On the other hand, the lowermost thinly tabular article **2** is supported by the first support **40** (raising member **70**) and the second support **50** different in level. The difference in level between the positions in the plane of the lowermost thinly tabular article **2** is out of the predetermined range **R**, and thus the lowermost thinly tabular article **2** is in an inclined posture. In the present embodiment, the adjuster **60** serving as an urging member that elastically urges the second support **50** upward is, for example, a wound spring with which the pivotal shaft **A1** of the second support **50** is provided.

The predetermined range **R** corresponds to a value set in advance on the basis of, for example, the thickness of the thinly tabular article **2** as a target or the dimension in the up-and-down direction of the passage to which the thinly tabular article **2** as the target is supplied. At the article supporter **5**, for example, the urging force of each adjuster **60** and the distance between the side walls **42** and **42** of each first support **40** and the leading end **53** of the corresponding second support **50** are appropriately set such that the uppermost thinly tabular article **2** is set within the predetermined range **R**.

The adjuster **60** adjusts the level of the leading end **53** of the second support **50** such that the difference in level between the thinner part **2X** and the thicker part **2Y** of the uppermost thinly tabular article **2** of the bundle **3** is smaller than the difference in level between the thinner part **2X** and the thicker part **2Y** of the lowermost thinly tabular article **2** of the bundle **3**.

<Raising Member>

The raising member **70** is a resin member detachably attached to the upper ends of the pair of side walls **42** and **42** of the first support **40**. The raising member **70** integrally includes an upper wall **71**, a front wall **72** extending downward from the front end of the upper wall **71**, and a rear wall **73** extending downward from the rear end of the upper wall **71**. The raising member **70** is fitted to the side walls **42** and **42** such that the raising member **70** is disabled from moving frontward and rearward.

<Third Support>

Such a third support **80** described above is a resin member integrally including a bottom wall **81**, a pair of side walls **82** and **82** extending upward, one-to-one, from both ends of the bottom wall **81** in the width direction. The bottom wall **81** is substantially the same in width dimension as the base **10**, and is detachably attached to the rear in the longitudinal direction of the base **10**. The third support **80** is provided behind the first support **40**, and supports a portion where the respective thinner parts **2X** of the thinly tabular articles **2** of the bundle **3** are superimposed on the upper face of the side wall **82** (see FIG. 8).

<Auxiliary Article Supporter>

Such an auxiliary article supporter **6** as described above is provided outside in the width direction of the article supporter **5**, and includes a base **110**, a support **120**, and an adjuster **130**.

<Base>

The base **110** is a resin member integrally including an elongated tabular bottom wall **111** extending frontward and rearward, a pair of side walls **112** and **112** extending upward, one-to-one, from both ends in the width direction at an intermediate part of the bottom wall **111** in the front-and-rear direction, and a handle **113** extending upward at the rear of the bottom wall **111**. The bottom wall **111** has a lower face on which, for example, a metal piece securable to the lifting plate **203** by magnetic force may be attached.

<Support>

The support **120** extends frontward and rearward, and integrally includes a base **121** and a leading end **122** in this order from the rear. The base **121** has a rear end accommodated between the pair of side walls **112** and **112**, and is journaled pivotally around the pivotal shaft **A2** to the pair of side walls **112** and **112**. With no bundle **3** supported, similarly to the base end **51** and the intermediate part **52** of the second support **50**, the base **121** inclines upward from rear to front in side view. With no bundle **3** supported, similarly to the leading end **53** of the second support **50**, the leading end **122** extends almost horizontally in side view. The support **120** supports a portion where the thicker parts **2Y** of the thinly tabular articles **2** of the bundle **3** are superimposed on the upper face of the leading end **122** (see FIG. 8). Further, at least either the base **110** or the support **120** is provided with a pivotal regulator that regulates, with no bundle **3** supported, pivoting of the support **120** such that the leading end **122** does not move upward from its horizontal position.

<Adjuster>

The adjuster **130** adjusts the level of the leading end **122** of the support **120** such that the uppermost thinly tabular article **2** of the bundle **3** is set within the predetermined range **R** (see FIG. 9) in the vertical direction. In the present embodiment, the adjuster **130** is as an urging member that elastically urges the support **120** upward and is, for example, a wound spring with which the pivotal shaft **A2** of the support **120** is provided.

<Relationship between Position and Level of Support>

With no bundle **3** supported, the upper face of the upper wall **71** of the raising member **70** externally fitted to the side walls **42** and **42** of each first support **40**, the upper face of the leading end **53** of the corresponding second support **50**, the upper faces of the side walls **82** and **82** of the corresponding third support **80**, the upper face of the leading end **122** of the corresponding support **120**, and the upper edge of the extending wall **23** are set at the same level. The leading end **53** of the second support **50** and the leading end **122** of the support **120** are at the same position in the front-and-rear direction and are arrayed in the width direction. The interval between the leading ends **53** of the pair of second supports **50** and **50** is smaller than the interval between the inner side walls **42** and **42** of the pair of first supports **40** and **40** and the interval between the inner side walls **82** and **82** of the pair of third supports **80** and **80**. In other words, the interval between the pair of first supports **40** and **40** and the interval between the pair of third supports **80** and **80** are set at a dimension in which the position regulator **204** can be disposed.

<Longitudinally-Long Open-End Envelope>

As illustrated in FIG. 5, in a direction orthogonal to the width direction, a longitudinally-long open-end envelope **2A** as an exemplary thinly tabular article **2** has, as a thicker part **2Y**, a bottom closed due to an overlapping margin and a part as a thinner part **2X** different from the bottom.

<Center-Seam Elongated Open-end Envelope>

As illustrated in FIG. 6, in a direction orthogonal to the width direction, a center-seam elongated open-end envelope **2B** as an exemplary thinly tabular article **2** has, as a thicker part **2Y**, a bottom closed portion due to an overlapping margin and a part as a thinner part **2X** different from the bottom. The center-seam elongated open-end envelope **2B** further has, as a thicker part **2Y**, a central part in the width direction closed due to an overlapping margin and the remaining part as a thinner part **2X** different from the thicker part **2Y**.

<Single-Side-Seam Elongated Open-End Envelope>

As illustrated in FIG. 7, in a direction orthogonal to the width direction, a single-side-seam elongated open-end envelope **2C** as an exemplary thinly tabular article **2** has, as a thicker part **2Y**, a bottom part closed due to an overlapping margin and a part as a thinner part **2X** different from the bottom. The single-side-seam elongated open-end envelope **2C** further has, as a thicker part **2Y**, one end in the width direction closed due to an overlapping margin and the remaining part as a thinner part **2X** different from the thicker part **2Y**.

<Technique of Supporting (Longitudinally-Long) Open-End Envelope>

As illustrated in FIGS. 8 and 9, a bundle **3** of longitudinally-long open-end envelopes **2A** stacked is supported by the article supporter set **4**, and is positioned by each first support **40**, and the position regulator **204** and the floaters **205** and **205** with the positions adjusted in response to the size of the longitudinally-long open-end envelopes **2A**. Of the bundle **3** of the longitudinally-long open-end envelopes **2A** stacked, a portion with the thinner parts **2X** superimposed is placed and supported on the upper wall **71** of the corresponding raising member **70** provided on the first support **40** and the side walls **82** and **82** of each of the corresponding pair of third supports **80** and **80**. Further, of the bundle **3** of the longitudinally-long open-end envelopes **2A** stacked, a portion with the thicker parts **2Y** superimposed is placed and supported on the leading end **53** of each second support **50** and the leading end **122** of the corresponding

support 120. Here, due to the weight of the thicker parts 2Y, the second support 50 pivots around the pivotal shaft A1 such that the leading end 53 is lowered while resisting the urging force of the corresponding adjuster 60. Further, due to the weight of the thicker parts 2Y, the support 120 pivots around the pivotal shaft A2 such that the leading end 122 is lowered while resisting the urging force of the corresponding adjuster 130. In such a state, (the respective upper faces of) the leading ends 53 and 122 inclining downward from rear to front in side view support the portion with the thicker parts 2Y superimposed of the bundle 3.

In such a state, of the lowermost open-end envelope 2A of the bundle 3, the thicker part 2Y is lower in position than the thinner part 2X. Of the uppermost open-end envelope 2A of the bundle 3, the thicker part 2Y is substantially the same in level as the thinner part 2X. That is, in the uppermost open-end envelope 2A, the positions of the thinner part 2X and the thicker part 2Y in the vertical direction fall within a predetermined range R (almost horizontal). That is, with the bundle 3 supported by the article supporter set 4, the difference in level between the thinner part 2X and the thicker part 2Y of the uppermost open-end envelope 2A of the bundle 3 is smaller than the difference in level between the thinner part 2X and the thicker part 2Y of the lowermost open-end envelope 2A of the bundle 3. The gap C between the uppermost open-end envelope 2A of the bundle 3 and the feeder 210 is set at a predetermined value.

As illustrated in FIG. 10, in a case where the bundle 3 becomes thinner due to outward supply of the open-end envelopes 2A of the upper part of the bundle 3, the controller 223 (see FIG. 1) causes the lifting plate 203 to lift. Each second support 50 (see FIG. 8) pivots around the pivotal shaft A1 such that the corresponding leading end 53 rises as the bundle 3 becomes lighter. Similarly, as the bundle 3 becomes lighter, the corresponding support 120 pivots around the pivotal shaft A2 such that the leading end 122 rises. At that time, the respective front ends of the remaining open-end envelopes 2A of the bundle 3 slide with respect to the rib 24. As a result, the gap C between the uppermost open-end envelope 2A of the bundle 3 and the feeder 210 is maintained at a predetermined value.

For a small number of stacked thinly tabular articles 2 of the bundle 3, the left and right raising members 70 as described above may be removed. In such a case, the portion with the thinner parts 2X superimposed of the bundle 3 is placed and supported on the side walls 42 and 42 of the corresponding first support 40.

Note that, in a case where all the open-end envelopes 2A of the bundle 3 are supplied outward, the controller 223 can stop the lifting of the lifting plate 203, due to detection of the extending wall 23 by the sensor 222.

<Technique of (Center-Seam Elongated) Open-End Envelope>

Next, a technique of supporting a center-seam elongated open-end envelope 2B will be described focusing on differences from the case of supporting a longitudinally-long open-end envelope 2A. In the drawings referred to in the following description, the floaters 205 and 206 and the feeder 210 are omitted appropriately. As illustrated in FIGS. 11 and 12, a bundle 3 of center-seam elongated open-end envelopes 2B stacked is supported by the article supporter 5, and is positioned by the position regulator 20, and the position regulator 204 and the floaters 205 and 205 with the positions adjusted in response to the size of the open-end envelopes 2B. Of such a center-seam elongated open-end envelope 2B as described above, the central part in the width direction as the thicker part 2Y locates between the leading

ends 53 and 53 paired in the width direction. Thus, the influence on the posture of the uppermost open-end envelope 2B is small. In the example of FIG. 11, the pair of front and rear third support 80 and 80 on the right are removed. The pair of front and rear third supports 80 and 80 on the right, however, are provided on the corresponding base 10.

<Technique of (Single-Side-Seam Elongated) Open-end Envelope>

Next, a technique of supporting a single-side-seam elongated open-end envelope 2C will be described focusing on differences from the case of supporting a center-seam elongated open-end envelope 2B. As illustrated in FIGS. 13 and 14, a bundle 3 with single-side-seam elongated open-end envelopes 2C stacked is supported by the article supporter 5, and is positioned by the position regulator 20, and the position regulator 204 and the floaters 205 and 205 with the positions adjusted in response to the size of the open-end envelopes 2C. Of the article supporter 5, the raising member 70 and each third support 80 corresponding to the one end in the width direction as the thicker part 2Y of such an open-end envelope described above 2C are removed. Such a configuration allows the article supporter 5 to cope with not only the difference in thickness of the open-end envelope 2C in the feeding direction but also the difference in thickness of the open-end envelope 2C in the width direction, so that the uppermost open-end envelope 2C can be substantially horizontal.

<Image Forming Apparatus>

The supply device 1 described above is suitably used as a device that supplies a thinly tabular article 2 to an image forming apparatus. Examples of such an image forming apparatus include a copier, a printer, a facsimile apparatus, a printing apparatus, and a multifunction peripheral. Hereinafter, a case where an image forming apparatus including the supply device 1 is applied to a copier will be described as an example.

As illustrated in FIG. 15, an image forming apparatus 301 according to an embodiment of the present invention includes an image-forming-apparatus main body 310, an image reader 320, an automatic document feeder 330, and the supply device 1.

The image-forming-apparatus main body 310 includes a storage 311, a supplier 312, an image former 313, and a discharger 314. The storage 311 stores a bundle of a plurality of thinly tabular articles 2 stacked. The supplier 312 takes out a thinly tabular article 2 from the thinly tabular articles 2 stored in the storage 311 and conveys the thinly tabular article 2 to the image former 313.

The image former 313 forms an image onto the thinly tabular article 2 conveyed from the supplier 312, on the basis of an image signal transmitted from the image reader 320. As an image forming type of the image former 313, for example, an electrophotographic type or an inkjet type can be adopted. As an example, in a case where the electrophotographic type is adopted for the image former 313, the image former 313 includes a toner-image forming unit, an intermediate transfer belt, and a fixer, and forms a toner image onto one main face of the thinly tabular article 2. In a case where the inkjet type is adopted for the image former 313, the image former 313 includes an inkjet head and forms an ink image onto one main face of the thinly tabular article 2.

The discharger 314 discharges the thinly tabular article 2 with an image formed by the image former 313, outward the image-forming-apparatus main body 310.

The image reader 320 optically reads an image from a document conveyed from the automatic document feeder

11

330, processes a read image signal, and transmits the processed image signal to the image former 313.

The automatic document feeder 330 includes a document table and conveys a document placed on the document table to the image reader 320.

The supply device 1 is connected to the image-forming apparatus main body 310 and supplies a thinly tabular article 2 to the image-forming-apparatus main body 310. In the present embodiment, the image forming apparatus 301 includes a plurality of such supply devices 1 as described above. Each supply device 1 separates the thinly tabular articles 2 one by one, and supplies each separated thinly tabular article 2 to the supplier 312 of the image-forming-apparatus main body 310.

The thinly tabular article 2 supported by the article supporter set 4 or the article supporter 5 is supplied to the supplier 312, with the thicker part 2Y facing frontward. The supply of the thinly tabular article 2 with the thicker part 2Y facing frontward is suitable for, for example, roller conveyance at the supplier 312 or sensor detection.

An article supporter 5 according to the embodiment of the present invention supplies a bundle 3 of a plurality of thinly tabular articles 2 that is stacked and is partially different in thickness, and includes: a first support that supports respective thinner parts 2X of the plurality of thinly tabular articles 2; a second support 50 that supports respective thicker parts 2Y of the plurality of thinly tabular articles 2 and is movable upward and downward; and an adjuster 60 that adjusts a level of the second support 50 such that the uppermost thinly tabular article 2 of the bundle 3 is set within a predetermined range R in a vertical direction.

Thus, the article supporter 5 enables suitable supporting of the bundle 3 with the plurality of thinly tabular articles 2 that is stacked and is partially different in thickness, so that the uppermost thinly tabular article 2 can take a suitable posture even for a large number of stacked thinly tabular articles 2.

In the article supporter 5, the adjuster 60 includes an urging member that urges the second support 50 upward.

Thus, the article supporter 5 enables lowering of the second support 50 downward due to the weight of the bundle 3, so that the uppermost thinly tabular article 2 can take a suitable posture.

In the article supporter 5, the second support 50 is pivotally journaled to the first support 40.

Thus, the article supporter 5 enables suitable setting of an angle of the face of the second support 50 supporting the bundle 3.

In the article supporter 5, the second support 50 includes a sensor holder 53a capable of a sensor 221 that detects presence or absence of the plurality of thinly tabular articles 2.

Thus, the article supporter 5 enables suitable detection of the presence or absence of the plurality of thinly tabular articles 2 supported by the article supporter 5.

The article supporter 5 further includes a raising member 70 detachably attached to an upper part of the first support 40.

Thus, the article supporter 5 enables changing of the support level of the thinner parts 2X in response to the number of stacked thinly tabular articles 2 of the bundle 3.

Further, in a case where the article supporter 5 includes first supports 40 paired in the width direction, the article supporter 5 can also suitably support a thinly tabular article 2 different in thickness in the width direction, such as a single-side-seam elongated open-end envelope 2C.

12

The article supporter 5 further includes a position regulator 20 that regulates, at a position lower than a position of the second support 50 not supporting the bundle 3, a position of an end of the bundle 3, the end being closer to the second support 50.

Thus, the article supporter 5 enables suitable prevention of the thinly tabular articles 2 of the bundle 3 from downstream displacement from the second support 50.

In the article supporter 5, the position regulator 20 has a face that is opposite the bundle 3 and is provided with a rib 24 extending upward and downward.

Thus, the article supporter 5 enables reduction of friction generated between the bundle 3 and the position regulator 20, so that the thinly tabular articles 2 of the bundle 3 can smoothly slide to the position regulator 20.

The article supporter 5 further includes a third support 80 that supports the bundle 3 and is opposite the second support 50 across the first support 40.

Thus, the article supporter 5 enables suitable supporting of the bundle 3 of thinly tabular articles 2 large in size in the feeding direction.

In the article supporter 5, the first support 40 includes a pair of first supports 40 and 40, the second support 50 includes a pair of second supports 50 and 50, the adjuster 60 includes a pair of adjusters 60 and 60, the first support 40, the second support 50, and the adjuster 60 are in a pair of combinations, one of the pair of combinations includes one of the pair of first supports 40 and 40, one of the pair of second supports 50 and 50, and one of the pair of adjusters 60 and 60, another of the pair of combinations includes another of the pair of first supports 40 and 40, another of the pair of second supports 50 and 50, and another of the pair of adjusters 60 and 60, and the pair of combinations are arrayed in a width direction of the bundle 3.

Thus, the article supporter 5 enables prevention of interference with a position regulator 204 that regulates the position of the end on the first support 40 side of the bundle 3 and prevention of warpage of the bundle 3 between the pair of second supports 50 and 50, resulting in suitable supporting of the bundle 3.

In the article supporter 5, the pair of second supports 50 and 50 have respective parts that support the bundle 3, the pair of first supports 40 and 40 have respective parts that support the bundle 3, and an interval between the respective parts of the pair of second supports 50 and 50 is smaller than an interval between the respective parts of the pair of first supports 40 and 40.

Thus, the article supporter 5 enables suitable positioning of the bundle 3 with the position regulator 204 large in size in the width direction.

The article supporter 5 further includes a coupler 30 that couples the pair of combinations and is provided with a handle 33.

Thus, the article supporter 5 enables facilitation of detachably attachment to a supply device 1 to which the article supporter 5 is applied.

According to the article supporter 5, each of the plurality of thinly tabular article 2 is as an envelope. Thus, the article supporter 5 enables suitable supporting of an envelope partially different in thickness.

A supply device 1 according to the embodiment of the present invention includes: the article supporter 5; and a feeder 210 that supplies, by air suction, an uppermost thinly tabular article 2 from a bundle 3 of a plurality of thinly tabular articles 2 that is stacked and is partially different in thickness, the bundle 3 being supported by the article supporter 5.

13

Thus, the uppermost thinly tabular article 2 as a feeding target is supported suitably, so that the article supporter 5 enables suitable feeding of the thinly tabular article 2.

The supply device 1 further includes floaters 205 and 206 that float the uppermost thinly tabular article 2 from the bundle 3 supported by the article supporter 5, and the feeder 210 feeds the floated thinly tabular article 2.

Thus, the uppermost thinly tabular article 2 as a feeding target is supported in a suitable posture, so that the article supporter 5 enables suitable floating and supplying of the thinly tabular article 2.

In the supply device 1, the second support 50 is disposed downstream of the first support 40 in the feeding direction of the plurality of thinly tabular articles 2.

Thus, the supply device 1 enables supplying of each thinly tabular article 2 with the thicker part 2Y facing frontward.

The supply device 1 further includes a lifting plate 203 movable upward and downward, and the article supporter 5 is provided on the lifting plate 203.

Thus, the supply device 1 can move the lifting plate 203 in response to the number of stacked thinly tabular articles 2 of the bundle 3 to disposed the uppermost thinly tabular article 2 at a position suitable for feeding.

An image forming apparatus 301 according to the embodiment of the present embodiment includes: the supply device 1; and an image former 313 that forms an image on each of the plurality of thinly tabular articles 2 supplied from the supply device 1.

Thus, because the uppermost thinly tabular article 2 as an image forming target is supported in a suitable posture, the image forming apparatus 301 enables suitable supplying of the thinly tabular article 2 to form suitably an image on the thinly tabular article 2.

Although embodiments of the present invention have been described and illustrated in detail, the disclosed embodiments are made for purposes of illustration and example only and not limitation. The scope of the present invention should be interpreted by terms of the appended claims, and thus can be appropriately changed without departing from the gist of the present invention.

What is claimed is:

1. An article supporter for a supply device including a feeder that supplies, by air suction, an uppermost thinly tabular article from a bundle of a plurality of thinly tabular articles that is stacked and is partially different in thickness, the article supporter for supporting the bundle with a gap between the uppermost thinly tabular article and the feeder, the article supporter comprising:

a first support that supports respective thinner parts of the plurality of thinly tabular articles;

a second support that supports respective thicker parts of the plurality of thinly tabular articles and is movable upward and downward; and

an adjuster that adjusts a level of the second support such that the uppermost thinly tabular article of the bundle is set within a predetermined range in a vertical direction, wherein the second support is disposed downstream of the first support in a feeding direction of the feeder, wherein each of the plurality of thinly tubular articles is an envelope,

wherein the second support supports a bottom part of the envelope, and

wherein the envelope is fed with the bottom part facing downstream in the feeding direction.

2. The article supporter according to claim 1, wherein the adjuster includes an urging member that urges the second support upward.

14

3. The article supporter according to claim 1, wherein the second support is pivotally journaled to the first support.

4. The article supporter according to claim 1, wherein the second support includes a sensor holder capable of holding a sensor that detects presence or absence of the plurality of thinly tabular articles.

5. The article supporter according to claim 1, further comprising a raising member detachably attached to an upper part of the first support.

6. The article supporter according to claim 1, further comprising a position regulator that regulates, at a position lower than a position of the second support not supporting the bundle, a position of an end of the bundle, the end being closer to the second support.

7. The article supporter according to claim 6, wherein the position regulator has a face that is opposite the bundle and is provided with a rib extending upward and downward.

8. The article supporter according to claim 1, further comprising a third support that supports the bundle and is opposite the second support across the first support.

9. The article supporter according to claim 1, wherein the first support includes a pair of first supports, the second support includes a pair of second supports, the adjuster includes a pair of adjusters, the first support, the second support, and the adjuster are in a pair of combinations,

one of the pair of combinations includes one of the pair of first supports, one of the pair of second supports, and one of the pair of adjusters,

another of the pair of combinations includes another of the pair of first supports, another of the pair of second supports, and another of the pair of adjusters, and the pair of combinations are arrayed in a width direction of the bundle.

10. The article supporter according to claim 9, wherein the pair of second supports have respective parts that support the bundle, the pair of first supports have respective parts that support the bundle, and an interval between the respective parts of the pair of second supports is smaller than an interval between the respective parts of the pair of first supports.

11. The article supporter according to claim 9, further comprising a coupler that couples the pair of combinations and is provided with a handle.

12. A supply device comprising:
the article supporter according to claim 1; and
a feeder that supplies, by air suction, an uppermost thinly tabular article from a bundle of a plurality of thinly tabular articles that is stacked and is partially different in thickness, the bundle being supported by the article supporter.

13. The supply device according to claim 12, further comprising a floater that floats the uppermost thinly tabular article from the bundle supported by the article supporter, wherein the feeder feeds the floated uppermost thinly tabular article.

14. The supply device according to claim 12, further comprising a lifting plate movable upward and downward, wherein the article supporter is provided on the lifting plate.

15. An image forming apparatus comprising:
the supply device according to claim 12; and
an image former that forms an image on each of the plurality of thinly tabular articles supplied from the supply device.
